ROTARY PUMP

Warren Hyre, Chattanooga, Tenn.

Application October 30, 1947, Serial No. 782,974

13 Claims. (Cl. 103—138)

1

This invention relates to improvements in rotary pumps and has for a principal object the provision of an improved positive action, sliding vane type of rotary pump capable of effectively pumping concrete, as well as other materials of a semi-fluid or viscous nature.

A rotary pump according to the invention is characterized by a two-part or sectional casing and the parts thereof may be axially separable and hinged connected whereby the casing may be readily opened up to permit washing out after each pour or run of the material being pumped, for example, for inspection of casing and rotor parts, and for repair and/or replacement of worn parts. The rotor is also preferably constructed in two halves which are bolted together whereby it may be readily disassembled for the purpose of repairing or replacing worn parts and thereupon reassembled with equal facility.

Another important feature of the invention is the provision of means whereby any material such as grout or sand working into the slide-ways provided in the rotor for the sliding pistons or vanes thereof, or along the sides of the rotor or vanes, is caused to pass harmlessly through the rotor or the casing end walls without damaging or causing undue wear of the casing and/or rotor parts. Simplified and readily replaceable wear and guide bushings for the moving parts of the rotor are employed throughout and, as a further feature of the invention, expanding packings effective against the faces of the sliding vane are provided for the purpose of sealing the rotor slide-ways against substantial leakage of the material being pumped along the faces of the vanes.

The above and other features and objects of a rotary pump according to the invention will appear from the following detailed description taken with the accompanying drawings illustrating a physical embodiment of the invention selected for the purpose of ready disclosure, it being understood that the invention is not limited to the specific details shown, in which—

Fig. 1 is a vertical section taken along line 1—1 of Fig. 2, illustrating interior construction of a rotary pump for pumping concrete and like materials according to the invention;

Fig. 2 is a section taken generally along line 2—2 of Fig. 1, the sliding pistons or vanes being omitted to illustrate details of rotor construction and mounting;

Fig. 3 is a section taken along line 3—3 of Fig. 2;

Fig. 4 is a detail view looking into the periphery of the rotor at the end of a slide-way provided therein;

2

Fig. 5 is a section taken along line 5—5 of Fig. 4, illustrating a preferred mode of packing the vanes at the outer end of the slide-ways in which the vanes operate;

5 Figs. 6 and 7 are detail section views taken on lines 6—6 and 7—7 of Fig. 1;

Figs. 8 and 9 are detail views illustrating the construction and intersecting relation of the sliding vanes operating in the rotor aforesaid; and

10 Fig. 10 is an enlarged detail view of a specially constructed hinge between casing parts which permits the pump casing to be readily opened up.

Referring to the drawings, reference character 15 15 8 (Figs. 1 and 2) generally designates a pump casing having an inlet 9 and an outlet 10. The casing may be of two-part construction, as shown, of which the parts 11 and 12 are preferably formed as castings which together are

20 adapted to provide a cylindrical pump chamber. Referring to Fig. 2, the casing part 11 is shown to be fixed to a stationary mounting plate 13, and the casing part 12 is adapted to be bolted to the fixed casing part 11 by means of a plurality of 25 spaced swing-bolts 14 hinged to lugs 15 projecting exteriorly from the fixed casing part. The free ends of the bolts 14 are adapted, in the assembled position of the casing parts, to pass into the bifurcations of correspondingly spaced lugs 16 projecting exteriorly from the casing part 12, and to be secured by nuts 17. Accordingly, by unthreading said nuts and by removing key 25 to be described, the movable casing 12 may be disconnected from fixed casing part 11 for the purpose of opening up the casing.

35 Suitable means are provided to support the movable casing part 12 in its opened-up position. Referring to Figs. 1, 2 and 10, such means preferably include fixed hinge bars 19, 20 extending from the base of the fixed casing part 11, each terminating in a narrow-width tongue 21. A hinge pin 22 connects each of the tongues with the forked end of a headed shank 23 provided with a through opening 24 for the reception of a locking key 25. As best seen in Fig. 10, movable 40 casing part 12, upon unthreading of bolts 17 and removal of locking keys 25, may be pulled axially outwardly from fixed casing part 11 for the length of studs 23 until it engages the heads 26 thereof which function as stops limiting axial separation of the casing parts. Upon the casing part 12 engaging the shank heads, its inner face

45 clears the hinge joints between hinge bar tongues 21 and studs 23, thus to permit the casing part 12 to be swung downwardly to its dotted-line position (Fig. 10). Since the hinge is capable of sup-

porting the movable casing part 12 in its dotted-line position, the operator is relieved of any requirement of holding the same in open position or of lowering it to a supporting surface.

Referring to Fig. 2, the casing parts 11, 12 are provided in their end walls with axially aligned hubs 27, 28 in which the pump rotor to be described has bearing, the hubs being accordingly formed eccentric to the casing axis. The end walls of each casing part are also provided with a plurality of radial slots 29 (Fig. 3) opening to the casing exterior whose function will be described.

Contained within the casing and mounted to turn on an axis eccentric to that of the pump chamber is a rotor generally designated 30. The rotor may be made in two half-sections, the halves 31, 32 thereof being rigidly although separably connected in face engagement by a plurality of circumferentially spaced bolts 33, the heads 34 thereof and their securing nuts 35 being accommodated in annular recesses formed in the inner faces of the end walls of the casing parts 11, 12 as shown in Fig. 2. The aforesaid slots 29 connect with said end wall recesses.

The rotor halves are each formed with oppositely extending trunnions 35, 36 adapted to be supported in the casing hubs 27, 28, the trunnions turning in suitable sleeve bearings 37, 37a contained in said hubs. Ring packings 38, 38a may be arranged between the inner radial faces of the hubs 27, 28 and the outer radial faces of the rotor halves and segmental wear and packing rings 39, 39a set into outer edge recesses formed in the rotor (Fig. 2) are effective between said outer edges and the casing end walls. Oil holes 41, 41a provide for lubricating said bearings.

A drive shaft 42 driven from a suitable source of power such as an electric motor (not shown) extends into the one trunnion 35 of rotor half 31 and drives the same and hence the rotor through a key 43. It will be observed that the drive shaft 42, rather than extending axially through the rotor in the conventional manner, terminates at about the inner end of the trunnion 35 to which it is drivingly connected. Since the rotor is bored for its full axial length, there results an open-ended central passage 44 which extends axially through the rotor from the end of the drive shaft to the casing exterior.

As seen in Fig. 1, the rotor is formed with intersecting, diametrical slide-ways 45, 46 which extend across and thus communicate with the axial passage 44 of the rotor. Intersecting, right-angularly disposed pistons or vanes 47, 48 are mounted to slide in said slide-ways. By reference to Figs. 8 and 9, the vanes may be of the two-section construction shown, the sections 47a, 47b and 48a, 48b thereof being disposed in tandem relation and urged outwardly of each other by pairs of springs 47c, 48c, respectively, coiled on spaced spring retaining legs 47d, 48d formed on the adjacent ends of the vane sections as shown. Since the vanes intersect one another, the spring retaining legs of one pair of vane sections, such as the sections 47a, 47b of vane 47, are spaced apart but a small distance so that they may be accommodated in and move across the greater space provided between the spring retaining legs of the sections 48a, 48b of the other vane. Accordingly, the vanes may operate independently of one another and without interference in their sliding motion through the rotor. The action of the vane springs 47c, 48c is to cause the tip edges of the vanes to engage against and follow the

outer peripheral wall of the pump chamber as the rotor turns in the casing, the sections of each vane withdrawing and expanding relative to each other during such rotation. As the width of the vanes at their outer or tip ends corresponds to that of the rotor and hence to the axial depth of the pump chamber, the material to be pumped entering inlet 9 of the pump chamber is propelled by the vanes to the pump chamber outlet 10 from whence it is discharged under positive pressure. Preferably, the vanes are tipped with rubber, neoprene or equivalent material whereby they may effectively seal against the peripheral wall of the pump chamber even though the material being handled incorporates coarse particles such as sand, gravel and the like. The pump chamber may also be lined with rubber, thus to reduce wear both on its surface and on the rubber tips of the vanes by the abrasive action of said coarse particles, as well as to cause more easy movement of the vanes.

Instead of forming the vanes with tandem sections as shown, they may be formed by two overlapping sections sliding on one another. If the casing is formed with an elliptical or substantially elliptical rather than circular chamber, the intersecting vanes may be of one-piece construction.

According to a further important feature of the invention, packing means effective against the faces of the sliding vanes are provided at the ends of the vane slide-ways. Referring to Figs. 4 and 5, such packing means preferably takes the form of strips or blocks 50, 51 of expansible packing material such as rubber, felt or the like extending the width of the vanes and being compressed into tight packing engagement with the opposite faces thereof by means of compressing screws 52, 53 threaded into the outer end faces of bearing guides 54, 55 disposed in the slide-ways inwardly of the packing. Said bearing guides may consist of blocks of bearing metal or of hard rubber, neoprene, fiber, felt or the like. It will be observed that the bearing guides and packing carried thereby are set into recesses provided adjacent the outer ends of the vane slide-ways. As seen in Fig. 5, the heads of the screws may seat on a metal strip 56 which is set into each packing strip to extend substantially the length thereof. By tightening the screws 52, 53, the packing strips 50, 51 are caused to expand into tight engagement against the faces of the vanes and to provide an effective seal therefor.

To prevent the packing strips from expanding in endwise direction, each strip is confined between annular confining rings 57, 58, which are secured against the outer side faces of the rotor by the bolts 33 which secure the rotor halves together. Said confining rings may carry pins 59 which extend into corresponding holes provided in the outer side edges of the bearing guides 54, 55, the pins thus serving to anchor the guides and the confining rings preventing any endwise expansion thereof beyond the end faces of the rotor.

According to a further feature of the invention, any material leaking past the packing strips 50, 51 is caused to pass harmlessly through the rotor to the casing exterior. For this purpose, the adjacent faces of the bearing guides 54, 55 on which the vanes bear may be formed with longitudinal corrugations or slots 54a, 55a (Fig. 7). Similarly, the adjacent walls of the slide-ways inwardly of the bearing guide are corrugated or slotted as indicated at 46a, 46b (Fig. 6),

the corrugations extending longitudinally and communicating with the corrugations of the bearing guides 54, 55. As the slide-ways open into the open-ended axial passage 44 of the rotor, it will be observed that any sand or grout working by the outer vane packings 50, 51 passes radially inwardly along the corrugations to the rotor bore, from whence it passes harmlessly to the exterior of rotor and casing. As respects any material leaking past the side faces of the rotor, such harmlessly discharges to the casing exterior through the slots 29 provided in the end walls of the casing.

It is also within the purview of the invention to prevent leakage of the material being pumped past the vane packings 50, 51, either by closing the slots 29 or by initially constructing the casing end walls without said slots, and thereupon forcing water or other suitable liquid under pressure through the open end of the rotor bore and thence radially outwardly through the slide-ways thereof, thereby water-sealing the slide-ways against entrance of sand, grout or like material through the outer ends of the slide-ways.

Without further analysis, it will be observed that a rotary pump as described is designed for and particularly adapted to the pumping of concrete and like materials of a coarse or semi-fluid or viscous nature. The hinged connection between the casing parts permits the casing to be opened up in a simple operation for washing out after each pour or run of the material, for inspection and for repair or replacement of worn parts. As the pump is designed for the handling of semi-fluid materials which may incorporate relatively coarse particles, provision is made for sealing off the vane slide-ways from any substantial leakage of the material into the slide-ways along both the faces and edges of the vanes. But in the event of such leakage, means are provided for effecting harmless passage of the material through the rotor or out of the casing end walls, so that undue wear or damage to the moving parts of the rotor or to the rotor itself is precluded. Since the pump casing may readily be opened up, all bearing and guide parts, which are themselves of simplified construction and of design permitting simple replacement, may be easily replaced when worn.

As the invention is not confined to the specific details illustrated, it is intended that all matter contained in the above description or shown in the accompanying drawings shall be interpreted as illustrative and not in a limiting sense.

I claim:

1. In a rotary pump, a casing having peripheral inlet and outlet passages and providing a pump chamber and having end walls, a rotor provided with a diametrical slide-way, a vane mounted to slide therein, a rotor driving shaft extending into the chamber through one end wall only of the casing and being drivingly connected to the rotor, the rotor having an axial passage opening through the other casing end wall, said passage being in communication with the slide-way, and the faces of the slide-way on which the vane slides incorporating leak means communicating with the axial passage, said leak means providing for the discharge of any material being pumped which may leak into the slide-way along the face of the vane.

2. In a rotary pump, a casing having peripheral inlet and outlet passages and providing a pump chamber and having end walls provided

with slots opening to the exterior of the casing, a rotor having a diametrical slide-way, a vane mounted to slide therein, a rotor drive shaft drivingly connected to said rotor, said end wall slots providing for the discharge of any material leaking past the edges of the vane or the side faces of the rotor to the casing exterior.

3. In a rotary pump, a casing having peripheral inlet and outlet passages and providing a pump chamber and having end walls provided with a material discharge opening to the exterior of the casing, a rotor provided with a diametrical slide-way, a vane mounted to slide in said way, the rotor having trunnions extending into aligned openings in the casing end walls and being journaled for rotation in bearings mounted in said openings, a rotor drive shaft having a drive connection with one of the rotor trunnions, the rotor and its other trunnion having an axial passage communicating with the rotor slide-way and extending to the exterior of the casing, and the faces of the slide-way on which the vane slides being provided with radial passages communicating with the axial passage, the construction and arrangement being such that any material being pumped which leaks past the edges of the vane and any such material which leaks past the faces of the vane may discharge to casing exterior.
4. In a rotary pump, a casing having peripheral inlet and outlet passages and providing a pump chamber, a rotor having a diametrical slide-way and an axial passage intersecting said slide-way and extending to casing exterior, a vane mounted to slide therein, the walls of the slide-way on which the vane has sliding bearing being formed with means providing radial passages for the radially inward movement to the axial passage of any of the material being pumped which may leak into the slide-way along the face of the vane.

5. In a rotary pump, a casing having peripheral inlet and outlet passages and providing a pump chamber, a rotor operatively mounted in the chamber and having a diametrical slide-way and an axial passage communicating with said way and extending to the casing exterior, a vane mounted to slide in the slide-way, the walls of the way on which the vane has bearing being formed with corrugations providing radial passages communicating with said axial passage and through which any of the material being pumped which may leak past the faces of the vane is carried to the exterior of the casing.

6. In a rotary pump, a casing having peripheral inlet and outlet passages and providing a pump chamber, a rotor operatively mounted in the chamber and having a diametrical slide-way and an axial passage communicating with said way and extending to the casing exterior, a vane mounted to slide in the slide-way, oppositely disposed bearing guides for the vane seating in recesses provided in the opposite walls of the slide-way adjacent its outer end, the faces of the guides adjacent the vane being provided with corrugations providing radial passages communicating with the axial passage and through which material leaking past the vane may discharge to casing exterior.

7. In a rotary pump, a casing having peripheral inlet and outlet passages and providing a pump chamber, a rotor having a diametrical slide-way, a vane mounted to slide therein, oppositely disposed bearing guides for the vane seating in recesses provided in the opposite walls of

the slide-way adjacent its ends and which open through the periphery of the rotor, compressible packing material adapted to seal against the faces of the vane and being mounted in said recesses outwardly of the bearing guides, and means for compressing said packing material against the outer end faces of the bearing guides.

8. In a rotary pump, a casing having peripheral inlet and outlet passages and providing a pump chamber, a rotor operatively mounted in said chamber and having a diametrical slide-way and an axial passage in communication with the slide-way and extending to the casing exterior, a vane mounted to slide in the slide-way, oppositely disposed bearing guides for the vane seating in recesses provided in the opposite walls of the slide-way adjacent its ends, the adjacent faces of the guides and walls of the slide-ways inwardly of the bearing guides being provided with corrugations openings into said axial passage and providing for the harmless passage through the rotor of any material being pumped which may leak into the slide-way along the faces of the vane.

9. In a rotary pump, a casing having peripheral inlet and outlet passages and providing a pump chamber, a rotor operatively mounted in said chamber and having a diametrical slide-way, a vane mounted to slide therein, resilient packing means extending the width of the vane adapted to seal against the faces of the vane and being positioned at the outer ends of the slide-way so as to normally prevent leakage of the material being pumped into the slide-way, means for compressing said packing means in radial inward direction thereby causing it to expand and seal against the faces of the vane, and means on the end faces of the rotor for confining the ends of the packing means against expansion in end-wise direction.

10. A rotary pump as set forth in claim 9, wherein the rotor is provided with an axial passage to casing exterior, and wherein the faces of the slide-way on which the valve slides are provided with corrugations forming radial passages extending between the packing means and the axial passage through which any of the material being pumped which leaks past the packing means may pass harmlessly to casing exterior.

11. In a rotary pump, a casing having peripheral inlet and outlet passages and providing a pump chamber, a rotor operatively mounted in said chamber and having a diametrical slide-way,

a vane mounted to slide therein, oppositely disposed bearing guides for the vane seating in recesses provided in the opposite walls of the slide-way adjacent its ends, packing for said vane disposed in the outer ends of said recess, means for compressing the packing against the outer end edges of the bearing guides thereby to expand the packing against the faces of the vane, and packing confining means carried by the rotor for preventing endwise expansion of the packing.

12. In a rotary pump as set forth in claim 11, wherein the packing confining means is also effective to locate and prevent endwise movement of the bearing guides.

13. A rotary pump as set forth in claim 11, wherein the rotor is provided with an axial passage to casing exterior, and wherein the faces of the guides adjacent the vane and the walls of the slide-way inwardly of said guides are provided with corrugations forming radial passages communicating with said axial passage, whereby any of the material being pumped which leaks past the packing may pass harmlessly to casing exterior.
